12 Claims. (Cl. 192—133)

1

This invention relates to the waste disposal art and, more particularly, to a device adapted for the comminution and disposal of garbage or other waste materials and which is suitable for home and restaurant use where only relatively small volumes of such materials are normally passed through the device. The present invention pertains to a waste disposal device of the type disclosed in my pending application for patent on Garbage Disposal Device, Serial No. 639,753, filed January 8, 1946, Patent No. 2,442,812, issued June 8, 1948, of which the present application is a division. Specifically, this application is concerned with a safety means embodied in the waste disposal device for guarding against injury to a human hand inserted into the device during a comminuting operation.

One object of the invention is to provide a waste disposal device, of the type referred to, having a comminuting chamber, a throat or passage leading to the chamber through which waste material may be passed to the chamber, and a safety means, in the form of a movable blocking member, disposed in the throat and adapted to be moved by a human hand thrust into the throat. It is another object of my invention to provide such a device in which the blocking member is so arranged that passage of waste materials through the throat and past the member is permissible but the insertion of a human hand through the throat during operation of the comminuting means is positively prevented.

Another object of the invention is to provide a waste disposal device having power-operated means for actuating the comminuting means, said power-operated means preferably consisting of an electric motor, and an electrical circuit for energizing the motor. It is a further object, in this respect, to provide a normally closed electric switch in the circuit for maintaining the circuit closed but adapted to be actuated by, and in response to movement of, the blocking member when the latter is engaged by a human hand, so as to open the circuit and deenergize the motor. By this means the operation of the comminuting means is stopped by the insertion of a human hand into the throat so that even though the hand is lowered into the comminuting chamber, it cannot be injured by the comminuting means.

Another object is to provide a safety means for the purpose indicated which is especially simple in construction, one which is easily applied to waste disposal devices, and one which is extremely sensitive and positive in action.

Further objects will be apparent from the fol-

lowing description and from the drawings, which are intended for the purpose of illustration only, and in which:

Fig. 1 is a vertical sectional view through a waste disposal device embodying the novel features of the present invention;

Fig. 2 is a cross-sectional view, taken on line 2—2 of Fig. 1; and

Fig. 3 is a wiring diagram of the electrical circuit for the disposal device.

Referring to the drawings, Fig. 1 shows a hopper unit 10 comprised of an outer section 11 and an inner section 12. The outer section 11 is provided at its upper end with an annular flange 13, by which the hopper unit 10 is supported by a mounting structure 14 beneath a conventional sink 15. As is usual, the sink 15 is provided with a depending annular flange 17 providing a drain opening 18 for the sink. The mounting structure 14 includes a sleeve member 19 adapted to fit into the drain opening 18 and having an annular flange 20 at the upper end thereof which seats on the sink 15, the lower end of the sleeve member being externally threaded to receive an annular plate 21. The plate 21 is spaced from the top of the flange 13 of the hopper unit 10 by an annular gasket ring 23, preferably formed of rubber or other resilient material, and the hopper unit is clamped relative to the plate 21 by means of vertical screws 24 passing through a lower annular plate 25 and the upper annular plate 21, the lower annular plate being spaced from the flange 13 by a lower gasket ring 26 also preferably formed of rubber or other resilient material. As will be understood, the mounting structure 14 provides means for resiliently mounting the hopper unit 10 beneath the sink 15 and permits the hopper unit 10 to be rotated through an arc of 360° relative to the mounting structure, in the manner and for the purpose explained in my pending application referred to previously.

The outer section 11 of the hopper unit 10 is provided with a boss 28 having an inlet opening 29 therein which communicates with the interior of the upper section 11, the boss being internally threaded to receive the end of a water supply pipe 30 leading to a suitable source of water under pressure (not shown). Disposed in the line of the water supply pipe 30 is a conventional solenoid actuated valve 31, adapted to alternatively open or close communication between the source of water in the water supply pipe 30 and the interior of the outer section 11. The outer section 11 is also provided with a depending tubular inner wall 32 which extends downwardly into the

upper end 12a of the inner section 12 and is spaced therefrom to provide an annular overflow port 32a therebetween. As will be noted, the overflow port 32a is disposed a substantial distance below the inlet port 29, and this insures that the liquid level in the hopper unit 10 cannot rise to the level of the inlet port 29.

The inner section 12 of the hopper unit 10 is concentric with the outer section 11 and has a main inner wall 40, the lower portion of which diverges outwardly and downwardly to form a comminuting chamber 41, the main inner wall 40 being spaced from the outer section 11 to form a space 39 therebetween.

Comminuting means are provided for comminuting waste material introduced into the chamber 41 by way of the throat, which includes the inner walls 32 and 40. The comminuting means is identical to that shown and described in the application referred to above, and, therefore, will not be described in detail herein. The comminuting means includes a series of stationary cutter elements 49 which are connected by screws 49a to ears 46 on the inner section 12. The cutter elements 49 project inwardly through openings in the section 12 and have cutting faces 52.

Disposed below the hopper unit 10 is a lower housing 58, which is rigidly secured to the outer section 11 of the hopper unit by means of suitable screws 59. As shown in Fig. 1, the ear elements 46 of the inner section 12 rest on the top face 57 of the lower housing 58 to support the inner section, and the inner section is rigidly clamped in position by the cooperation of the outer section 11 and the lower housing. The lower housing 58 has an annular and substantially horizontal wall 60 which forms the bottom of an annular discharge chamber 61 which has formed integrally therewith or connected thereto a discharge pipe fitting 62 adapted to receive a suitable discharge fitting 63 which leads to a sewer or other waste material connection (not shown).

The lower housing 58 also has an outer tubular depending wall 65 to the lower end of which is suitably secured an electric motor 66, the wall having openings 67 therein so as to permit the discharge of air from the interior of the lower housing. The motor 66 is provided with a vertical drive shaft 68 extending upwardly therefrom and having on it a fan 69, the fan being adapted in response to rotation of the drive shaft 68 to draw air through the motor and discharge such air through the openings 67, to cool the motor windings.

To the upper end of the drive shaft 68 is rigidly fixed a rotatable table element 71, which includes a rotary cutting means of the invention. The rotatable table element 71 has an upwardly projecting boss 72 in the center thereof which substantially obstructs the center of the table element and to which is rigidly fixed the rotatable drive shaft 68 by means of a screw 73. The top of the rotatable table element 71, outwardly from the boss 72, is slightly conical in form, providing a dished upper surface 74, the outer rim 75 of which extends into close proximity with the inner wall 40 of the inner section 12 of the hopper unit 10, being spaced slightly upwardly from the lower end thereof. The clearance between the outer rim 75 and the inner wall 40 is maintained as small as possible so as to prevent the passage of comminuted material therethrough during operation of the device, which is very undesirable in my invention.

Projecting from the outer rim 75 of the rotat-

able table element 71 are a plurality of cutter knives 79 which extend into the discharge chamber 61 so as to provide only a slight clearance with the flat bottom of each of the stationary cutter elements 49. As illustrated in Fig. 1, the cutter knives 79 are relatively thin and are disposed so that the knives will not create any appreciable centrifugal pumping effect in the annular discharge chamber 61 which might otherwise overload the motor 66. The cutter knives 79 cooperate with the flat bottom 58 of each of the stationary cutter elements 49 to form secondary cutting means of the invention.

Provided on the dished upper surface 74 of the rotatable table element 71 is a pair of movable cutters 80 which are rotatably mounted on the table element 71 by means of pins 82, only one such cutter being herein shown. The pin 82 projects from the movable cutter 80 on one side of the longitudinal center line thereof so as to place the center of gravity of the cutter on one side of the axis of the pin, so that when the table element 71 is rotated by the drive shaft 68, centrifugal force acting on the movable cutter 80 will rotate it relative to the element 71 to the cutting position in which it engages a suitable stop pin (not shown). The movable cutter 80 is provided with an outer cutting face 86 which is adapted to cooperate with the cutting faces 52 of the stationary cutter elements 49 to comminute garbage or other waste material therebetween. The stop pins prevent the movable cutters 80 from rotating into actual engagement with the stationary cutter elements 49. By so retaining the movable cutters 80 in cutting position merely by centrifugal force exerted by the rotatable table element 71, it will be understood that the movable cutters may rotate back to retracted position in the event that a non-comminutable material, such as a metal object or glass, finds its way into the comminuting chamber 41, thus preventing damage to the cutting faces 52 and 86.

As illustrated in Figs. 1 and 2, disposed in the upper portion of the outer section 11 of the hopper unit 10 is a safety device 103 which constitutes a blocking or obstructing means of the invention, adapted to deenergize the electric motor 66 when the safety device is moved, so as to protect against the possibility of a human hand being inserted into the hopper unit during rotation of the rotatable table element 71. The safety device 103 includes a rod 104 having a blocking or obstructing head 105 thereon, the rod being rigidly fixed to a transverse supporting rod 106 which in turn is rotatably supported by suitable sleeve bearings 107 formed integrally with the outer wall of the outer section 11.

One end of the rod 106 projects out of its bearing 107 and has secured rigidly thereto a sleeve 108 provided with an extending arm 109 disposed perpendicular to the sleeve and rod. Also formed on or secured to the outer wall of the outer section 11 is a switch box 110 having a conventional electric switch 111 therein, the switch being provided with a push button 112 which is normally held in depressed position by the arm 109. The switch 111 is of a conventional type in which electrical contact is made when the push button 112 is depressed and such electrical contact is broken when the push button is released, as by a suitable spring (not shown). The arm 109 and the switch box 110 may be temporarily locked together by a soft wire 113 passing through each. It will be apparent that downward movement of the rod 104 and head 105, due to attempted insertion of a hand into the hopper unit 10 or other-

wise, rotates the supporting rod 106 and the arm 109, breaking the soft wire 113 and moving the arm out of engagement with the push button 112 to permit the latter to move outwardly to break the electrical circuit to be described hereinafter. To again close the electrical circuit requires that the push button 112 be manually depressed and the arm 109 manually rotated back to its retaining position as shown. This manual resetting operation is not difficult, but tends to be aggravating to the operator and, consequently, acts to deter the operator from thrusting his hand into the hopper unit except when it is essential to do so. The rod 104 and head 105 are sufficiently small that garbage may readily pass thereby into the hopper unit 10 without actuating the safety device 103.

The electric circuit shown in Fig. 3 illustrates one side of the electric motor 66 connected by a wire 115 through a main switch 116 to one wire 117 of the electric current main. The other side of the motor 66 is connected by a wire 119 to the switch 111, which in turn is connected to the other wire 119' of the current main. In parallel with the motor 66, but also controlled by the main switch 116, is a conventional solenoid 120 adapted to actuate the solenoid actuated valve 31. The solenoid 120 and the solenoid actuated valve 31 are of any conventional type in which the valve is maintained open by the solenoid so long as the solenoid is electrically energized so as to permit passage of fluid through the supply pipe 30. When the solenoid 120 is deenergized, suitable spring means (not shown) return the solenoid actuated valve 31 to closed position so as to shut off the flow of fluid through the supply pipe 30.

In operation, garbage or other waste material is placed in the hopper unit 10, through the sleeve member 19, until the chamber 41 of the hopper unit is substantially filled. The main switch 116, diagrammatically illustrated in Fig. 3, is then manually closed, which completes the electrical circuit through the electric motor 66 and energizes the same. At the same time, the solenoid 120 is similarly energized to open the solenoid actuated valve 31 to permit a flow of water or other flushing fluid through the supply pipe 30 into the hopper unit 10 through the inlet opening 29. Energization of the electric motor 66 rotates the vertical drive shaft 68 to similarly rotate the rotatable table element 71.

Upon rotation of the rotatable table element 71, centrifugal force operating on the movable cutters 80 rotates the same to their cutting positions illustrated in Fig. 1, in which position they cooperate with the stationary cutter elements 49 to comminute the garbage or other waste material disposed in the chamber 41.

The garbage or other waste material in the chamber 41 is rotated with the rotatable table element 71 by the movable cutters 80 and is thrown to the periphery of the rotatable table element by centrifugal force so that as it passes the stationary cutter elements 49 it is comminuted by the action of the movable cutters 80 acting therewith or by the stationary cutters alone, the smaller pieces thereof being moved outwardly through vertical discharge slots (not shown) by centrifugal force and by the thrust of the movable cutters 80 and by the action of the water in the chamber 41, the garbage or waste material then falling into the discharge chamber 61, from which it is flushed by the flushing liquid through the discharge fitting 63.

It will be readily apparent that if a human hand, for example the hand of the person using the device, was inserted into the comminuting chamber 41, during operation of the comminuting means, the hand would be seriously injured by the relatively rotating cutters 49 and 80. Such an occasion might arise if the person attempted to retrieve an object inadvertently placed in the disposal device. Such an extremely hazardous condition is entirely avoided in my present improved waste disposal device because the safety means functions to arrest the operation of the comminuting means before the hand can reach the rotating cutters.

15 Assuming that the device is in operation and waste material is being comminuted in the chamber 41, if for any reason the attendant of the device inserts his or her hand into the device through the open upper end thereof, the hand 20 will contact the obstructing or blocking head 105 of the safety device 103. It will be noted by reference to Fig. 2 that sufficient clearance is provided between the head 105 and the unit wall 32 to permit bits of waste material to pass 25 through the throat into the comminuting chamber 41 but that such clearance is insufficient to allow a human hand to pass through the throat without engaging the head. Consequently, when a hand is inserted into the throat, it pivots the 30 rod 104 in counter-clockwise direction, as viewed in Fig. 1, so that the arm 109 is pivoted upwardly, breaking the locking wire 113.

During such upward pivotal movement of the arm 109, the push button 112 of the normally 35 closed switch 111 is released and permitted to move outwardly to open the switch. In this manner, the electrical circuit is opened and the electric motor 66 is deenergized. Due to resistance offered by the material in the comminuting 40 chamber to the rotation of the table element 71 and the cutters 80, the motor 66 is promptly brought to rest. It is therefore seen that even though the hand is slid downwardly into the comminuting chamber, injury to the hand will 45 be avoided since the comminuting operation is completely arrested at this time.

To subsequently close the electrical circuit, the push button 112 must be manually depressed and the arm 109 rotated back to its retaining position to maintain the button in switch closing 50 position. While such resetting of the switch is not difficult, it tends to be aggravating to the operator and, consequently, discourages the thrusting of a hand into the hopper unit except 55 when it is essential to do so. It will thus be seen that my improved safety means is highly efficient in guarding against injury to the operator and in no way impairs the normal insertion and comminuting of waste material.

60 Although I have shown and described a preferred embodiment of my invention, it will be understood by those skilled in the art that many modifications can be made in the present construction without departing from the spirit of the 65 invention, and, consequently, I do not intend to be limited by the specific embodiment illustrated and described herein, but desire to be afforded the full scope of the appended claims.

I claim as my invention:

70 1. In a waste disposal device, the combination of: hopper means having a vertical opening and defining a vertical comminuting chamber; comminuting means in said chamber adapted to comminute waste material therein; an electric motor 75 for actuating said comminuting means; an elec-

trical circuit for said motor; a switch connected in said circuit and disposed outside said hopper means; a shaft pivoted in the walls of said hopper means and projecting therefrom; a rod carried by said shaft within said opening and provided with a blocking member; and an arm carried by said shaft outside said hopper means and normally engageable with said switch to maintain said switch closed and said motor energized, said arm being adapted to open said switch in response to pivotal movement imparted to said blocking member and said shaft by a human hand inserted into said opening.

2. In a waste disposal device, the combination of: hopper means having a vertical opening and defining a vertical comminuting chamber; comminuting means in said chamber adapted to comminute waste material therein; an electric motor for actuating said comminuting means; an electrical circuit for said motor; a switch connected in said circuit and disposed outside said hopper means; a shaft pivoted in the walls of said hopper means and projecting therefrom; a rod carried by said shaft within said opening and provided with a blocking member; an arm carried by said shaft outside said hopper means and normally engageable with said switch to maintain said switch closed and said motor energized, said arm being adapted to open said switch in response to pivotal movement imparted to said blocking member and said shaft by a human hand inserted into said opening; and a releasable locking element normally engaged with said arm to lock said arm in switch closing position, said element being released in response to a force applied thereagainst by said arm to unlock said arm and permit movement thereof to switch opening position.

3. In a waste disposal device, the combination of: hopper means having a vertical opening and defining a vertical comminuting chamber; comminuting means in said chamber adapted to comminute waste material therein; an electric motor for actuating said comminuting means; an electrical circuit for said motor; a switch connected in said circuit and disposed outside said hopper means; a shaft pivoted in the walls of said hopper means and projecting therefrom; a rod carried by said shaft within said opening and provided with a blocking head; an arm carried by said shaft outside said hopper means and normally engageable with said switch to maintain said switch closed and said motor energized, said arm being adapted to open said switch in response to pivotal movement imparted to said blocking head and said shaft by a human hand inserted into said opening; and a deformable locking element normally engaged with said arm to lock said arm in switch closing position, said element being adapted to be deformed in response to a force applied thereagainst by said arm to unlock said arm and permit movement thereof to switch opening position.

4. In a waste disposal device, the combination of: hopper means having a vertical opening and defining a vertical comminuting chamber; comminuting means in said chamber adapted to comminute waste material therein; actuating means for actuating said comminuting means; movable control means for controlling the energization of said actuating means, said control means being normally active to maintain said actuating means energized; and pivoted obstructing means having a blocking head disposed in said opening adapted normally to permit waste material to be introduced into said chamber

through said opening, said obstructing means normally being operatively connected to said control means to maintain the same active so as to maintain said actuating means energized, 5 said blocking head being engageable by a human hand inserted in said opening, pivotal movement of said obstructing means in response to engagement of the hand with said blocking head causing disconnection of said obstructing means from 10 said control means so as to effect de-energization of said actuating means by said control means.

5. In a waste disposal device, the combination of: hopper means having a vertical opening and defining a vertical comminuting chamber; comminuting means in said chamber adapted to comminute waste material therein; actuating means for actuating said comminuting means; movable control means for controlling the energization of said actuating means, said control means being normally active to maintain said actuating means energized; and pivoted obstructing means having a blocking head disposed in said opening adapted normally to permit waste material to be introduced into said chamber through said opening, 15 said blocking head being engageable by a human hand inserted in said opening to cause pivotal movement of said obstructing means, said obstructing means normally engaging said control means to cause the same to maintain said actuating means energized but adapted upon 20 pivotal movement in response to engagement of said blocking head by the hand inserted into said opening to disengage said control means so as to effect de-energization of said actuating means.

6. In a waste disposal device, the combination of: hopper means having a vertical opening and defining a vertical comminuting chamber; comminuting means in said chamber adapted to comminute waste material therein; actuating means for actuating said comminuting means; movable control means for controlling the energization of said actuating means, said control means being normally active to maintain said actuating means energized; pivoted obstructing means having a blocking head disposed in said opening adapted normally to permit waste material to be introduced into said chamber through said opening, 25 said blocking head being engageable by a human hand inserted in said opening to cause pivotal movement of said obstructing means, said obstructing means normally engaging said control means to cause the same to maintain said actuating means energized but adapted upon 30 pivotal movement in response to engagement of said blocking head by the hand inserted into said opening to disengage said control means so as to effect de-energization of said actuating means.

7. The combination defined in claim 6 including an electric circuit, said actuating means comprising an electric motor in said circuit, said control means comprising a switch in said circuit and having a plunger adapted to be depressed manually to close said switch, said obstructing means normally being disposed in a first position to engage said plunger to maintain the same depressed but adapted upon pivotal movement to a second position in response to engagement of said blocking head by the hand to release said plunger so as to effect opening of said circuit, 35 said locking means being deformable in response to a predetermined force exerted by said ob-

structing means to release said obstructing means.

8. The combination defined in claim 7 in which said obstructing means is pivoted in a plane normal to the axis of said switch plunger and adapted to be pivoted to said first position to overlie the end thereof following manual depression of said plunger so as to maintain said switch closed, said obstructing means releasing said plunger when pivoted to said second position so as to permit said plunger to move to extended position to open said switch, return pivotal movement of said obstructing means to said first position being prevented by said plunger in extended position and permitted only after said plunger has been manually restored to circuit closing position.

9. In a waste disposal device, the combination of: hopper means having a vertical opening and defining a vertical comminuting chamber, said opening being sufficiently large to permit the passage of a normal adult human hand therethrough; comminuting means in said chamber adapted to comminute waste material therein; obstructing means pivotally mounted on a substantially horizontal axis and extending into an approximately central portion of said opening and being of a size to prevent the passage of such a hand through said opening without actuating said obstructing means, said obstructing means being sufficiently small to permit waste material to be introduced into said chamber through said opening and past said obstructing means without actuating said obstructing means; power means for actuating said comminuting means; control means operatively connected with said power means; and connecting means operatively connected between said control means and said obstructing means for operation of said control means upon movement of said obstructing means for de-energizing said power means.

10. In a waste disposal device, the combination of: hopper means having a vertical opening and defining a vertical comminuting chamber below said opening, said opening being sufficiently large to permit the passage of a normal adult human hand therethrough; comminuting means in said chamber adapted to comminute waste material therein; power means for actuating said comminuting means; obstructing means pivotally mounted and extending into said opening in an exposed position within said opening and of a size to prevent the passage of such a hand through said opening without moving said obstructing means, said obstructing means being sufficiently small to permit waste material to be introduced into said chamber through said opening without moving said obstructing means; and control means for de-energizing said power means; and connecting means operatively connecting said control means to said obstructing means for operation of said control means in response to pivotal movement of said obstructing means to de-energize said power means.

11. In a waste disposal device, the combination of: hopper means having a vertical opening

and a vertical comminuting chamber below said opening, said opening being sufficiently large to permit the passage of a normal adult human hand therethrough; comminuting means in said chamber adapted to comminute waste material therein; an electric motor for actuating said comminuting means; an electrical circuit for said motor; a switch in said circuit; and obstructing means extending into said opening and of a size to prevent the passage of such a hand through said opening without moving said obstructing means, said obstructing means being sufficiently small to permit waste material to be introduced into said chamber through said opening without moving said obstructing means, said obstructing means being operatively connected to said switch to normally maintain said switch closed and said motor energized but adapted to open said switch to de-energize said motor in response to movement of said obstructing means.

12. In a waste disposal device, the combination of: hopper means having a vertical opening and a vertical comminuting chamber below said opening, said opening being sufficiently large to permit the passage of a normal adult human hand therethrough; comminuting means in said chamber adapted to comminute waste material therein; an electric motor for actuating said comminuting means; an electrical circuit for said motor; a switch in said circuit; and obstructing means pivotally mounted with respect to said hopper means on a substantially horizontal axis and extending into said opening and of a size to prevent the passage of such a hand through said opening without moving said obstructing means, said obstructing means being sufficiently small to permit waste material to be introduced into said chamber through said opening without moving said obstructing means, said obstructing means being operatively connected to said switch to normally maintain said switch closed and said motor energized but adapted to open said switch to de-energize said motor in response to movement of said obstructing means.

HANS JORDAN.
